(57) **CLAIM**

The ornamental design for a faucet temperature sensor and display, as shown and described.

DESCRIPTION

FIG. 1 is a perspective top view of a faucet temperature sensor and display showing my new design;

FIG. 2 is a side view; opposite side view is a mirror image thereof;

FIG. 3 is a front view thereof;

FIG. 4 is a back view thereof;

FIG. 5 is a top view thereof;

FIG. 6 is a bottom view thereof;

FIG. 7 is a perspective bottom view; and,

FIG. 8 is a perspective view showing the spout broken away to indicate indeterminate length thereof.
